DESIGN FOR A COMBINATION SPRINKLER AND HAIR SCRUBBER

Nathan L. Solomon, Mount Vernon, N. Y.

Application February 4, 1942, Serial No. 105,637

Term of patent 14 years

To all whom it may concern:

Be it known that I, Nathan L. Solomon, a citizen of the United States and residing at Mt. Vernon, in the county of Westchester and in the State of New York, have invented a new, original, and ornamental Design for Combination Sprinkler and Hair Scrubber, of which the following is a specification, reference being had to the accompanying drawing, forming a part thereof wherein:

Fig. 1 is a top plan view of a combination sprinkler and hair scrubber showing my new design.

Fig. 2 is a front elevational view of Fig. 1, and Fig. 3 is a bottom plan view of Fig. 2.

I claim:

The ornamental design for a combination sprinkler and hair scrubber, substantially as shown.

NATHAN L. SOLOMON.
